(57) **CLAIM**

The ornamental design for a trap panel, as shown and described.

DESCRIPTION

FIG. 1 is a perspective view of a trap panel of the present invention;

FIG. 2 is a front elevational view of the trap panel of FIG. 1; FIG. 3 is a front elevational view of an enlarged portion of the trap panel of FIG. 1;

FIG. 4 is a rear elevational view of the trap panel of FIG. 1; FIG. 5 is a bottom plan view of the trap panel of FIG. 1, of which the top view is a mirror image thereof;

FIG. 6 is a right side elevational view of the trap panel of FIG. 1, of which the left side view is a mirror image thereof;

FIG. 7 is an enlarged view of a portion of the trap panel of FIG. 1, taken along the dashed line of FIG. 1;

FIG. 8 is an enlarged view of a portion of the trap panel of FIG. 1, taken along the dashed line of FIG. 2;

FIG. 9 is a perspective view of the trap panel of FIG. 1, showing the panel used to form a portion of a trap; and, FIG. 10 is an enlarged view of the trap panel of FIG. 9, taken along the dashed line of FIG. 9.

The broken line showing of FIGS. 9 and 10 are for the purpose of illustrating the environmental structure and form no part of the claimed design.

The dashed line showing of FIGS. 1, 2, 7, 8, 9 and 10 are for illustrating the area in which enlarged views are taken and form no part of the claimed design.
